ELECTRICAL CONNECTOR

Harold Lockton, Berkeley, Calif.

Application September 27, 1945, Serial No. 618,862

4 Claims. (Cl. 173—343)

1

This invention relates to means whereby conductors associated with electrical work circuits may be instantaneously connected to or disconnected from conductors associated with electrical supply circuits.

It is an object of the invention to provide an adapter permitting connection, to a marine type service outlet, of any one of a variety of dissimilar plug connectors classified as non-marine types.

Another object of the invention is to provide an adapter for the purpose described which will receive both push and twist types of plug connectors.

A further object of the invention is to provide an adapter of the character referred to which is ultimately compact in size and composed of but few parts which are sufficiently substantial to resist damage or breakage due to abnormal rough handling.

Still another object of the invention is to provide an adapter, for use on shipboard, which will greatly lessen the work of the ship's electricians in assisting land-based repair or maintenance crews to accommodate their power tools, which are usually equipped with standard spade plugs, to the special service outlets associated with the ship's current distribution system.

The invention possesses other objects and features of advantage which, together with the foregoing, will be specifically brought out in the detailed description of the invention hereunto annexed. It is to be understood that the invention is not to be limited to the specific form thereof herein shown and described as various other embodiments thereof may be employed within the scope of the appended claims.

Referring to the drawing:

Figure 1 is a top plan view of the adapter of my invention.

Figure 2 is a vertical sectional view of the adapter taken in the plane indicated by the line 2—2 of Figure 1.

Figure 3 is a bottom plan view of the adapter.

Figure 4 is a horizontal sectional view taken in the plane indicated by the line 4—4 of Figure 2.

Figure 5 is a side elevational view of the adapter.

Figure 6 is a horizontal sectional view taken in the plane indicated by line 6—6 of Figure 5.

Figure 7 is a horizontal sectional view taken in the plane indicated by the line 7—7 of Figure 2.

Electrical service outlets associated with the power circuits of the average ship are of a spe-

2

cial type utilizing a socket adapted to receive a cylindrical push-type plug which is held in place after insertion by a screw collar functioning to render the socket waterproof. On numerous occasions, land-based service firms are called upon to do repair or maintenance work on the ships and often, upon arriving on the job, find that the conventional prong type connectors, with which their electric drills and other such tools 10 were equipped, would not fit the marine type sockets. Time then had to be taken by the contractors or ship's electricians to equip their work leads with the marine type plugs before work could be started, and in the event that the ship's stores did not contain extra plugs, a trip ashore was necessary to procure them.

I have provided an adapter by means of which any of the generally used standard plugs may be quickly connected to the push type marine 20 service outlets and will provide the usual secure and waterproof connections with the outlets or their mounting boxes. The adapter comprises a cylindrical plug portion 8, composed of suitable material such as molded Bakelite, in which is embedded a pair of relatively insulated and diametrically opposed metallic bus bars 9 which emerge from the plug adjacent its lower end to form opposed electrical contacts 11. This plug portion is designed for axial insertion into the cylindrical receiving recess of a marine type socket wherein the contacts 11 establish connection with suitable corresponding terminals provided in the socket recess. Certain marine 30 sockets are provided with pins or lugs extending radially inwardly from the recess periphery, so as to insure that the plug may be inserted in only one way, and to accommodate this particular design the plug is provided on one side with a longitudinally extending groove 12 to receive the pin or lug. In another design of socket, the plug-receiving recess is not a true circle but is provided with a chordally extending flat portion and, to permit fitting of the adapter of my invention to such sockets, I provide the plug portion 8, on the side thereof opposite the groove 12, with a chordally and axially extending flat 13.

Means is provided whereby after the plug portion 8 of the adapter has been inserted into the 40 socket it may be locked therein and sealed against the entrance thereto of moisture. Molded into the plug portion 8 and arranged concentrically thereof at a position spaced upwardly from the plug end, is a metallic ring 14 provided at its 50 upper end with a radially extending annular

flange 16 having an annular gasket 17 contiguously engaging its lower face. The position of the flange 16 relative to the lower end of the plug portion 8 is such that when the plug is fully inserted in its receiving socket, and the contacts 11 properly engage their mating current conducting elements within the socket, the gasket 17 will engage and will be capable of being compressed against the upper end of the socket or the end of a ring-shaped extension of the terminal box in which the socket is contained. Means for compressing the gasket and effecting the lock and seal is provided comprising a diametrically divided ring having an annular flange 18, extending axially and concentrically of the plug, which is provided with internal screw threads 19 engageable with mating threads formed on the exterior of the aforesaid upper end of the socket or ring-shaped extension of the terminal box. The ring 18 is also provided with a radial flange 21, overlying the plug 16 and the two sections of the ring are secured together by a peripheral band 22 which may be pressed or sweated onto the respective sections. The assembly thus forms an annular nut which when engaged with its similarly threaded mating element will both lock the plug in its socket and will forcibly squeeze the gasket against the element so as to effect a water-tight seal.

Means are provided for effecting electrical connection to the respective bus bars 9 of a variety of standard type connector plug elements. The upper end of the plug 8, above the annular nut just described, is provided with an integral, diametrically expanded flange 23 having an upwardly extending peripheral rim 24 provided, as is best shown in Figure 5, with a notch 26. A cylindrical cap 27, also constructed of molded Bakelite or material of a similar nature, is positioned concentrically with and abutting the upper end of the plug section and is provided in its lower end with an annular groove 28 for receiving the rim 24. An abutment 29 formed in the groove 28 enters the notch 26 and serves to secure the cap 27 and plug member 8 against relative rotational movement, and a screw 31 passing through an aperture 32 formed centrally of the upper end of the plug and tapped into a central hub 33 in the cap serves to secure the cap and the plug together against relative axial displacement. The screw 31 is inserted in place through a recess 34 extending axially upwardly into the plug member 8 from the bottom end of the latter. The cap 27 is provided in its upper surface with a pair of T-shaped apertures 36 and also with a pair of arcuate apertures 37, one of each type aperture being arranged to open into a chamber 38 of a pair thereof formed in the cap. In each chamber is a set of contacts comprising a finger 39, arranged to be engaged by a prong inserted into the chamber through that portion of the aperture 36 forming the cross-bar of the T, a pair of fingers 41 adapted to be engaged by a prong inserted through the portion of the aperture 36 forming the leg of the T, and a pair of arcuate fingers 42 which are engageable by a curved prong inserted through the aperture 37. All of the foregoing fingers are connected together as an integral unit and are also connected to one of the bus bars 9. The cross-bar portions of the apertures 36 accommodate the most common type of connector plug wherein the prongs are in spaced relation with their respective broad faces paralleling each other, while the leg por-

tions of the apertures 36 provide for reception of the less common plug type wherein the prongs are disposed edgewise in a common plane. The arcuate apertures 37 accommodate the type of plug called "Twistlock" wherein the transversely curved prongs, which are arranged with their concave faces in opposition, are inserted into the apertures after which the plug is rotated relative to the receiving member so as to lock the plug in place. This type of connector is used extensively in industrial installations.

It will be seen that the head or cap 27 of the adapter provides for the connection of practically all types of plugs which will usually be encountered in the course of the average job, and the adapter is designed with a view toward compactness so that it may be readily carried in the tool kit or in the worker's pocket.

Having thus described my invention in detail, 20 what I claim as new and desire to secure by Letters Patent is:

1. An adapter comprising a plug member having a separate head member at one end thereof provided with recesses and apertures entering 25 said recesses for the reception of connector prongs, means to connect said plug and head members together, conductors extending longitudinally and within the body of said plug member, said conductors terminating at one end in contacts exposed at the periphery of and at diametrically opposed points on said plug member, said conductors at the other end thereof entering the respective head member recesses, contact fingers connected with said other end of the 30 conductors and positioned within said recesses to be engaged by said connector prongs, and an internally threaded ring member concentric with and journaled on said plug member.

2. An adapter comprising a cylindrical plug member having a separate head member arranged in axial concentricity therewith, said head member being provided with recesses and apertures entering said recesses for the reception of connector prongs, means to connect said plug and head members together against relative axial and rotational displacement, a pair of diametrically opposed bus bars extending longitudinally of and within the body of said plug member, said bus bars at one end of said plug member being each directed radially outwardly to terminate at the surface of the plug member in an exposed contact, the opposite end of each bus bar extending into the respective head member recesses, and contact fingers carried by said bus bars in the respective recesses and engageable by 40 said connector prongs.

3. An adapter comprising a cylindrical plug member having a separate head member arranged in axial concentricity therewith, said head member being provided with recesses and sets of apertures entering said recesses for the reception of connector prongs, one set of said apertures being adapted to receive parallel and planar aligned prongs and another set of said apertures being adapted to receive relatively curved prongs, a pair of diametrically opposed bus bars extending longitudinally of and within said plug member, said bus bars at one end thereof being directed radially outwardly of the plug member to terminate at the surface of the latter in exposed contacts and at the other end thereof entering the respective head member recesses, and sets of contact fingers carried by 45

said bus bars and aligned with the respective sets of apertures in said head member.

4. An adapter for connection to a socket having a receiving recess provided with current-conducting elements and an externally threaded sleeve member concentric with said receiving recess, a cylindrical plug of insulating material adapted for axial insertion into said receiving recess, means to limit the relative positions of said receiving recess and plug during the insertion of the latter into the receiving recess, a cylindrical head member of insulating material secured to an end of said plug in axial concentricity therewith, said head member having recesses therein and apertures entering said recesses for the reception of connector prongs, a pair of bus bars extending longitudinally of and within said plug member, said bus bars at one end thereof being directed radially outwardly of the plug to terminate at the surface of the latter in exposed contacts engageable with the current-conducting elements of the receiving recess, the

other end of said bus bars entering the respective head member recesses, contact fingers carried by the bus bars and engageable by the contact prongs inserted into said head member recesses through said apertures, and an internally threaded annular nut concentric with and journaled on said plug to engage said sleeve member to secure the plug in said receiving recess.
